(57) **CLAIM**

The ornamental design for a shell for a USB receptacle connector, as shown and described herein.

DESCRIPTION

FIG. 1 is a perspective view of a shell for a USB receptacle connector showing the new design;

FIG. 2 is a front view thereof;

FIG. 3 is a rear view thereof based on FIG. 2;

FIG. 4 is a left-side view thereof based on FIG. 2;

FIG. 5 is a right-side view thereof based on FIG. 2;

FIG. 6 is a top view thereof based on FIG. 2;

FIG. 7 is a bottom view thereof based on FIG. 2; and,

FIG. 8 is another perspective view thereof based on FIG. 1.
